J. W. KNOWLTON

SPIKE PULLING DEVICE

Filed May 27, 1922

Patented Apr. 8, 1924.

1,489,355

UNITED STATES PATENT OFFICE.

JERRY W. KNOWLTON, OF VANCOUVER, BRITISH COLUMBIA, CANADA.

SPIKE-PULLING DEVICE.

Application filed May 27, 1922. Serial No. 564,080.

To all whom it may concern:

Be it known that I, JERRY W. KNOWLTON, a subject of Canada, residing at Vancouver, in the Province of British Columbia and 5 Dominion of Canada, have invented certain new and useful Improvements in Spike-Pulling Devices, of which the following is is specification.

This invention relates to spike pulling devices and has for its object the provision of means whereby spikes may be withdrawn without bending the same.

A further object is to provide a spike pulling device which by reason of the arrangement of the levers may be operated by 15 one man and without excessive effort.

A further object of the invention is to provide a spike pulling device wherein the upward pull exerted on the spike is utilized 20 to more firmly grip the jaws of the pulling device with the head of the spike.

A further object is to provide a spike pulling device which is of highly simplified construction, durable in use and cheap to 25 manufacture.

Other objects and advantages of the invention will be apparent during the course of the following description.

In the accompanying drawing forming 30 a part of this application and in which like numerals are employed to designate like parts throughout the same,

Figure 1 is a side elevation of the improved spike pulling device in use.

Figure 2 is a detailed front elevation illustrating the spike engaging means.

Figure 3 is a fragmentary perspective of a handle embodied in the invention.

In the drawing wherein for the purpose 40 of illustration is shown a preferred embodiment of the invention the numeral 5 designates a base from which a pair of spaced parallel standards 6 extend and as illustrated in Figures 1 and 2 the standards are 45 braced by a pair of oppositely arranged reinforcing ribs 7.

A lever 10 is pivoted intermediate its ends between the standards 6 by means of a pivot element 11 and the rear portion of 50 the lever has connection with a pair of links 14 by means of a pivot element 15.

In carrying out the invention the lower 55 portions of the links 14 are pivoted as indicated at 18 to the lower portion of the handle 20 which forms a means whereby the spikes

may be elevated. The forward portion of the handle 20 is formed with a downwardly projecting ear 22 having an aperture 24 for the reception of a pivot element 25 which extends through the spaced parallel standards 6. More specifically the standards 6 are provided with rearwardly directed extensions through which the pivot element 25 is extended. The downwardly projecting ear 22 is arranged somewhat below the handle 20 so that the pivot element 25 is connected to the handle in such a manner that a maximum leverage is obtained.

In carrying out the invention a pair of head members 28 are pivotally connected to the forward portion of the lever 10 by means of a pivot element 30 and the lower portions of the head members 28 are provided with apertured ears 32 between which links 34 are connected by means of pivot elements 35. The lower portions of the links are connected to the apertured ears 37 formed at the rear ends of the jaws 39.

As illustrated in Figure 2 the jaws 39 are crossed and are pivotally connected at 40. A coiled spring 42 is confined between the ears 37 and is connected to lugs 43 carried by the opposed sides of the ears. Also leaf springs 48 are connected to the ears 37 as indicated at 49 and serve to urge the jaws firmly into engagement with the head of the spike 50 being removed.

In operation the jaws 39 are engaged with the head of the spike and the handle 20 which is curved longitudinally is engaged 50 and moved downwardly so as to elevate the spike engaging member. As the lever 10 is rocked the jaws 39 are more firmly engaged with the head of the spike so that the accidental disconnection of the spike engaging means from the spike is prevented. It will be seen that the spike 50 is withdrawn without the bending of the same so that the spike 55 may be used a number of times.

Having thus described the invention, 100 what is claimed is:—

1. A spike removing device consisting of a standard, a lever pivoted intermediate its ends to the standard, a pair of head members pivoted to the forward portion of said lever and provided with pairs of downwardly directed apertured ears, links connected to said ears, a pair of pivotally connected jaws having their rear portions formed with ears pivoted to said links, a 105

spring arranged between said second named ears, and leaf springs connected to said second named ears and engaging said jaws.

2. A spike removing device consisting of a standard, a lever pivoted intermediate its ends to the standard, a pair of head members pivoted to the forward portion of said lever and provided with pairs of downwardly directed apertured ears, links connected to said ears, a pair of pivotally connected jaws having their rear portions

formed with ears pivoted to said links, a spring arranged between said second named ears, leaf springs connected to said second named ears and engaging said jaws, and a handle having connection with said standard and said lever and being curved longitudinally.

JERRY W. KNOWLTON.
